UNITED STATES PATENT OFFICE.

HARRISON R. LELAND, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA.

GAS-TIGHT STEEL TANK.

Application filed November 11, 1920. Serial No. 423,291.

To all whom it may concern:

Be it known that I, HARRISON R. LELAND, a citizen of the United States, residing at Parkersburg, in the county of Wood and State of West Virginia, have invented certain new and useful Improvements in Gas-Tight Steel Tanks, of which the following is a specification.

This invention relates to oil tanks, and it 10 comprises the combination with a gas-tight tank, of an automatic positive and negative acting differential pressure regulator, the regulator being arranged to maintain a predetermined pressure in the tank to retard evaporation, but to permit escape of gases when the pressure exceeds a certain limit, and being further arranged to permit entrance of air when oil is withdrawn from the tank.

20 The invention further comprises a tank which is absolutely gas-tight, and in which leakage of oil, or evaporation, is reduced to a minimum. Since the introduction of the use of metal tanks for storing oil, the losses 25 have been reduced. When oil is stored in wooden tanks, there is not only a large loss due to evaporation, but there is a further loss due to seepage through the walls of the tank. The use of metal tanks has eliminated 30 loss due to the latter cause, but heretofore, the tanks have been so constructed that losses due to evaporation have been very great. While the bottom and side walls of the oil 35 tanks have been provided with packing to prevent leakage, the top or deck has been given little consideration with the result that large openings have been left in the deck of the tank, permitting free flow of air into the tank and free flow of evaporated 40 oil and gas from the tank.

The losses due to evaporation have, in the past, been enormous. Furthermore, the lighter and more volatile constituents of hydrocarbon oils which are in greatest demand, 45 form the greatest portion of the oil lost through evaporation.

In the present invention, I have provided an oil tank wherein, the parts are arranged to practically eliminate evaporation. The 50 deck of the tank is made absolutely gas-tight and is provided with packing where it joins the side walls of the tank to prevent entrance of air. I have further provided a differential pressure regulator which prevents the

escape of gases formed in the tank, or present 55 in the oil, until a predetermined pressure is reached. When a pressure is reached above which it would be unsafe to confine the gases, they are permitted to escape. The gage further serves as a means for permitting introduction of air when oil is withdrawn from the tank.

The tank is capable of use as a storage tank or as a flow tank, and may be employed 60 as a combined flow and storage tank.

In the accompanying drawings, I have shown one embodiment of the invention. In this showing:

Figure 1 is a vertical sectional view of the tank,

Figure 2 is a horizontal sectional view on line 2—2 of Figure 1,

Figure 3 is a top plan view,

Figure 4 is a detail view of the clean-out plate,

Figure 5 is a sectional view on line 5—5 of Figure 4,

Figure 6 is a detail sectional view showing the manhole dome.

Figure 7 is a detail view of the filling pipe,

Figure 8 is a sectional view on line 8—8 of Figure 3,

Figure 9 is a detail sectional view of the bottom of the tank,

Figure 10 is a detail sectional view showing the method in which the bottom and deck are joined to the side walls,

Figure 11 is a sectional view on line 11—11 of Figure 1, taken in the direction of the arrows, and,

Figure 12 is a detail sectional view on line 12—12 of Figure 3.

Referring to the drawings, the reference numeral 1 designates the bottom of the tank, which is provided with side walls 2, and a deck 3. The bottom and the deck of the tank are each constructed of a plurality of separate plates cut to a predetermined size and provided with spaced openings for the reception of bolts or other fastening means. (See Figures 2 and 3.) The separate plates forming the bottom and deck of the tank are joined to each other by a lap seam joint and are provided with suitable packing to prevent leakage.

Referring to Figure 9 of the drawings, the plates 4 which form the bottom and deck of the tank are arranged with their adjacent ends overlapping and with

the openings in alignment with each other. A strip of packing 5 is arranged between the overlapping portions of the plate. A channel iron 6, having spaced openings, is placed beneath the bottom plate with its openings in alignment with the openings in the plates. Bolts 7 are passed through the aligning openings, the heads 8 of the bolts being disposed in the channel iron to prevent displacement 10 and a nut 9 is placed on the threaded ends of the bolts.

The means for securing the bottom and deck to the side walls is shown in detail in Figure 10 of the drawings. The end of the side wall is provided with a flange 10 adapted to lie beside the plate 4, forming the outer edge of the tank or deck. The flange and the edge of the plate are provided with a series of openings adapted to be arranged 15 in alignment with each other. Bolts 11 are placed in these openings and nuts 12 are arranged on the bolts. A strip of packing 13 is arranged between the flange 10 and the edge of the plate.

25 In manufacturing oil tanks, it is customary in the trade to construct a tank in two sections. Thus, a thousand barrel tank is of the same diameter as a five hundred barrel tank, but is twice as high. When a 30 tank of two sections is to be constructed, the flanges 10 on the meeting edges of the sections of the side wall 2 are provided with a strip of packing and secured to each other by bolts 14 (see Figure 1). The deck of 35 the tank is supported by rafters 15, secured to the side walls. The deck is provided with the usual man-hole opening, adapted to receive a man-hole dome 16, and is further provided with thief-hole openings 17, adapted 40 to receive thief-hole covers 18. The deck is so constructed as to prevent leakage through the thief-hole and man-hole openings. The deck plate 4 around the man-hole opening extends inwardly toward the 45 center of the opening about one inch beyond the man-hole ring and in the same plane. To this one inch extension is bolted the man-hole dome by means of bolts 16', the joint being made gas-tight by use of packing 17'. 50 The man-hole cover 18' is secured to the man-hole dome and made gas-tight by means of packing 19'. The dome proper is flanged top and bottom, as at 20', and the dome cover may be bolted or unbolted from the 55 outside by bolts 21', thus facilitating a means of entering or leaving the interior of the tank. The dome offers a convenient arrangement for flanged connections and pipe by means of which gas may be conveyed to the atmosphere or to condensers. 60 As shown, the edge of the plate of the deck around the thief-hole is embossed or offset as at 19, and the thief-hole cover is provided with similarly embossed edges 20 to 65 so fit the edge 19 of the opening as to form

a gas-tight construction by the use of suitable packing 24'. In the present disclosure, I have shown the thief-hole covers secured to the deck of the tank by means of hinges 22', the hinges being secured to the deck 70 plate as at 21, and to the thief-hole cover, as at 22. Opposite the hinge, a hasp 25' is arranged on the thief-hole cover, and a staple 27' is received in this hasp. A wedge 26' may be arranged in the staple to insure 75 tight closure of the thief-hole cover.

It is advisable to secure the thief-hole cover to the deck of the tank in some manner to prevent its loss. If the thief-hole is allowed to remain open, the gas-tight feature of the tank is lost and its effectiveness 80 is reduced. Any suitable means may be employed to secure the thief-hole cover to the deck of the tank and prevent its loss.

The tank is provided with the usual ladder 85 23 arranged in the center and extending from the man-hole opening to the bottom of the tank. In the present construction, I have provided means for supporting the ladder, said means comprising a man-hole ring 90 24 (see Figure 6), having an arm 25, which is secured to the rafters by means of bolts 26. The other arm 27 of the man-hole ring supports a leg of the ladder and, as shown, they are secured to each other by means of 95 bolts 28.

The tank is provided with a filling connection 30, extending through an opening 31 in the top of the tank and connected to a filling pipe 32. The filling pipe is inclined and terminates at a point near the bottom of the tank. As shown, the filling pipe is provided with a longitudinal opening 33. Being inclined, the filling pipe prevents the oil from falling from the top of 100 the tank to the surface of the oil in a partial spray, but carries it rapidly in a compact stream to the surface of the oil where it flows out gently through the longitudinal opening 33 into the tank. Oil thus conveyed 105 into the tank will present the least possible surface to the air and evaporation will be reduced to a minimum. Through the longitudinal opening 33, any gas which may flow or be pumped into the tank with the oil may 110 escape into that part of the tank not occupied by oil. The tank is provided with the usual outlet opening 34 and with a clean-out plate 35 (see Figures 4 and 5) having an opening 36. As shown, the clean-out 115 plate is provided with a flange 37, adapted to overlie the flange 10 of the side wall and a strip of packing 38 is arranged between the clean-out plate and the tank side and flange 10. A threaded flange 39 is arranged 120 in the clean-out plate and is adapted to receive standard pipe connections.

The automatically acting differential pressure regulator 40 is arranged on the top or deck of the tank. The regulator may be 125

placed on the man-hole cover so as to permit its removal, but in the accompanying drawings, I have shown it on a slightly enlarged scale and for clarity of presentation, have shown it arranged on the deck. As shown, the deck of the tank is provided with an opening 41, adapted to communicate with the gage through a pipe 42. The gage is provided with two chambers 43 and 44, separated from each other by a partition wall 45, and communicating through a passage 46, at the bottom of the partition wall. Each of the chambers is provided with a plurality of baffles 47. The gage is provided with an outlet pipe 48, provided with a hinge cover or fire door 49. As shown, the cover is provided with a counterweight 50, adapted to maintain it in open position. A wire 51 is connected to the cover and extends to a suitable point near the ground to permit control of the cover. The two chambers of the gage are provided with openings and plugs 52 to permit introduction of a liquid into the gage.

As stated, the tank may be employed as a flow tank or as a storage tank, or as a flow and storage tank. On property where production is light, the tank may be used as a combined flow and storage tank. The construction of the various parts of the tank is such that no gases may escape or air enter except under pressure through pipe 42. The crude oil in the tank has an affinity for the light hydrocarbons which have passed from it (evaporated) under the following circumstances:

When the air in the tank and immediately in contact with the oil is saturated with the light hydrocarbons;

When some saturated air is subjected to slight pressure, such as is maintained by the differential pressure regulator herein described.

These conditions are supplied and maintained by first supplying a gas-tight deck and pressure regulator, and second inducing oil into the tank, displacing the saturated air, thus creating pressure. As the tank fills, a certain amount of gaseous air must escape through the pressure regulator. During the whole period, however, a large amount of the gases are being absorbed by the oil. This reduces the losses due to evaporation to a minimum.

The operation of the automatically acting differential pressure regulator is as follows:

Any suitable liquid is placed in the bottom of the regulator through the inlets 52. The liquid will normally assume the same level in each chamber designated by the reference numeral 53. Any gas in the tank will create a pressure in the chamber 43 and tend to disturb the normal level of the liquid, as designated by the dotted lines 54 and 55. The parts of the regulator are

so constructed that when a predetermined pressure is reached within the tank, the lever 54 in the chamber 44 will be forced down below the passage 46. Gas will then bubble up through the liquid contained in the chamber 43, and exhaust through pipe 48. When the tank is being emptied and a partial vacuum is created by the withdrawal of the oil from the tank, atmospheric pressure in the chamber 44 will force the level of the liquid down below the passage 46 and air will bubble through the liquid and pass into the tank through pipe 42.

Any suitable liquid may be employed in the regulator. I have found that crude oil is highly satisfactory for this purpose, as it is readily obtainable at the point where the tank is to be used and it will absorb a certain amount of the lighter constituents escaping in gaseous form. As these light constituents are the most desired constituents of oil, it is highly advantageous to employ crude oil and absorb them.

The various dimensions of the pressure regulator and the connecting pipe 42 must be predetermined in view of the pressure desired in the tank. A variable intake and outlet pressure may be obtained by varying the cross-sectional area of the chambers 43 and 44. The baffles in the chambers 43 and 44 are provided to furnish a more constant pressure, to minimize fluctuations, and to baffle escape of globules of gage fluid. If the baffles were not employed, there would be a sudden rush of gas into the gage at any time that a body of gas were present in the tank, due to various reasons, and the action would probably be sufficiently violent to carry off a portion of the liquid in the regulator. Through the use of baffles 47, the pressure is held more constant as the flow of gas is retarded and distributed over a longer period of time. The size of the baffles is important and their cross-sectional area must be determined and properly proportioned to the area of the chambers.

It is to be understood that while I have shown the preferred embodiment of my invention, various changes in the shape, size, and arrangement of parts may be resorted to without departing from the spirit of the invention or the scope of the subjoined claims.

Having thus described my invention, I claim:

1. A pressure regulator for tanks comprising a casing, a partition wall arranged substantially centrally thereof and extending from the top of the casing to a point near the bottom to provide a pair of chambers communicating with each other at the bottom of the casing, each of said chambers being provided with openings arranged at the top thereof, one of said openings being

connected to an inlet pipe and the other of said openings to an outlet pipe, a normally open valve arranged in said outlet pipe, and means for closing said valve.

5. A pressure regulator for tanks comprising a substantially rectangular casing having a vertical partition wall arranged substantially centrally thereof and extending from the top of the casing to a point near the bottom thereof to provide a pair of chambers communicating with each other

at the bottom, each of said chambers being provided with openings at the top forming an inlet and an outlet, baffles arranged in said chambers, said chambers being adapted 15 to receive a liquid arranged to flow from one chamber to the other, and means for introducing the liquid into the casing.

In testimony whereof, I affix my signature.

HARRISON R. LELAND.
